UNITED STATES PATENT OFFICE.

JOHN M. MORTON, OF CEDAR RAPIDS, IOWA.

COMBINED MAT AND SCRAPER.

SPECIFICATION forming part of Letters Patent No. 543,999, dated August 6, 1895.

Application filed May 27, 1895. Serial No. 550,886. (No model.)

To all whom it may concern:

Be it known that I, JOHN M. MORTON, a citizen of the United States, residing at Cedar Rapids, in the county of Linn and State of Iowa, have invented certain new and useful Improvements in a Combined Mat and Scraper for Cars, &c.; and I do hereby declare the following to be a full, clear, and exact description of the invention, such as will enable others skilled in the art to which it appertains to make and use the same.

The object of this invention is to produce a combined scraper and mat specially adapted to railway-cars, hallways, and other interiors, the construction being such as to secure a proper cleaning of the feet on entering, the depositing of the dirt in a pan underneath, the easy removal thereof, and the entire closure of the hole in the floor which receives said device.

The invention consists in the construction, combination, and arrangement of parts, as hereinafter fully set forth and claimed.

In the accompanying drawings, forming a part of this specification, Figure 1 is a plan view of a device embodying my invention. Fig. 2 is a longitudinal section in vertical planes, the right half of the figure being central to Fig. 1 and the left half in the line xx .

Similar letters of reference indicate corresponding parts.

Referring to the drawings, A designates the sill or floor-timber of a railway-coach or the floor-joists of a dwelling. B is the floor laid thereon, which is commonly double, as shown. In this is cut a hole to receive the lower portion of a tray C, the flanges C' of which rest on the adjoining floor, and in the case of a car should be secured thereto, as by screws $a a$. At a suitable distance from the top of this tray a shoulder C'' is formed all around the inside to serve as a support for the grate D.

This grate has a series of transverse bars $d d$ about half its length, the upper edges of which are practically flush with the upper surface of the tray-flanges, and serve as scrapers to remove dirt from the sole of the foot. The other half of the grate is in the nature of a tray with a perforated bottom, having a recess to receive the mat E, which should stand a little higher than the grate, as shown. This mat is fastened to the grate, as

by wires $b b$, so that when the grate is turned up on end to remove the dirt below the mat does not fall out of place. In the tray below 55 the grate is placed a removable pan F to catch the dirt falling through the scraper part and sifting down through the mat. The tray has a closed bottom, as shown, to close the hole made in the floor and exclude cold 60 air. This is especially essential in the case of railway-coaches, the floors of which are exposed directly to the outside air.

The grate has a hinged connection with the tray, by means of offset-lugs D' D' passing 65 down through holes c c formed in the flanges of the tray. These lugs prevent detachment of the grate at this end while the grate is in a horizontal position, and when raised to an upright position, as indicated by the dotted 70 lines, the lugs abut on the end of the tray and hold the grates slightly inclined backward, as shown. The other end of the grate is provided with a combined handle and latch G, hinged between lugs d' d' formed at the end 75 of the grate. A downwardly-extending portion of this handle G has a hook g' formed thereon to catch under the shoulder formed in the tray, and thus holds the grate down at this end while the handle is in its normal de- 80 pressed position. The other portion of the handle proper G fits normally in a recess or socket c' in the flange of the tray, the upper portion of the handle being flush with the surface of said flange when in this position. 85 The backward movement of the hook g' is limited by a shoulder c'', against which the handle abuts, as indicated by the dotted outline. The handle thus turns far enough to disengage the hook and give space for the 90 fingers of the operator without unnecessarily increasing the size of the aperture through the flange of the tray and the floor.

The device is primarily adapted for use in railway-coaches, and is designed to be set in 95 the aisle near the door, with the scraper nearer the door than the mat. In the case of neat and careful persons the scraper will be used designedly, as well as the mat, while in the case of thoughtless passengers much of 100 the dirt on their shoes will be scuffed off as they cross the grate and mat unconsciously.

The importance of fastening the grate down in railway-coaches will be apparent from the

fact that accidents are likely to occur, and the grate should not fall out of its place in the tipping or overturning of a car.

Having thus described my invention, I claim—

1. The combination with the floor of a railway coach or other apartment, of the tray C having marginal flanges and a closed bottom, and provided with supporting ledges or shoulders inside, the grate D having transverse bars d d about half its length and a recess the other half to hold a mat, said grate being hinged to the tray, and provided with suitable means for holding it in normal position, and for lifting one end, a mat secured in said recess, and a pan set in said tray below the grate, to catch the dirt falling through.
2. The combination with the floor of a rail-

way coach or other apartment, of the tray C, having marginal flanges C', shoulder C'', holes c c , and socket c', the grate D having transverse bars d d occupying about half its length, a perforated recess formed in the remainder thereof, and provided with lugs D' D' and d' d', the mat E secured in said recess, the handle G having latch g g' hinged to lugs d' d' and having a limited movement to engage and disengage with the tray, and a pan F set in the tray below said grate, substantially as and for the purpose set forth.

In testimony whereof I affix my signature in presence of two witnesses.

JOHN M. MORTON.

Witnesses:

J. M. ST. JOHN,
FRANK CHRISTLE.
